MONORAIL CAR

William H. Statler, Northridge, Calif., assignor to Lockheed Aircraft Corporation, Burbank, Calif.

Filed Feb. 10, 1960, Ser. No. 59,338

Term of patent 14 years

(Cl. D66—1)

Figure 1 is a front perspective view of a monorail car showing my new design;

Figure 2 is a rear elevational view thereof;

Figure 3 is a front elevational view thereof;

Figure 4 is a side elevational view thereof; and

Figure 5 is a top plan view thereof.

The track shown in broken lines in Figure 1 is included for illustrative purposes only. The side not shown is a mirror image of the side shown.

I claim:

The ornamental design for a monorail car, as shown and described.
